UNITED STATES PATENT OFFICE.

ADDISON D. LODGE, OF VANDALIA, OHIO.

WHIFFLETREE-HOOK.

SPECIFICATION forming part of Letters Patent No. 597,008, dated January 11, 1898.

Application filed May 22, 1897. Serial No. 637,711. (No model.)

To all whom it may concern:

Be it known that I, ADDISON D. LODGE, a citizen of the United States, and a resident of Vandalia, Montgomery county, State of Ohio, have invented certain new and useful Improvements in Whiffletree-Hooks; and my preferred manner of carrying out the invention is set forth in the following full, clear, and exact description, terminating with claims particularly specifying the novelty.

This invention relates to carriages and wagons, and more especially to the whiffletree-hooks used thereon for the removable attachment of the traces; and the object of the same is to produce such a hook adapted for removable attachment to whiffletrees of different sizes for adjustment in its position after attachment and to avoid scratching the paint.

To these ends my invention consists in a whiffletree hook or attachment constructed substantially as hereinafter more fully described and claimed, and as illustrated in the accompanying drawings, wherein—

Figure 1 is a plan view of the right end of a whiffletree with this hook or attachment in position and closed on the trace, the latter being shown in dotted lines. Fig. 2 is a perspective view of the attachment itself removed from the whiffletree and with the arm thrown back.

In the said drawings the letter W designates one extremity of an ordinary whiffletree, preferably and usually having a shoulder S on its rear side near its outer extremity, beyond which it is reduced and possibly pointed, so as to receive the cockeye of the trace T, as usual. This forms no part of the present invention, but is illustrated in order to show the application and operation of my invention.

The letter O designates an oval piece of spring-wire having both ends rounded, as shown, and the ends of the wire are preferably connected at one of such rounded ends in the manner shown—that is to say, one extremity of the wire has a flat eye F and the other is turned upward and pointed, as at P, so that it may pass through the eye F and upward into the under side of the whiffletree, if desired. However, this is a matter of preference entirely, for the extremities of the

wire could be soldered or brazed together or the entire oval could be stamped or cut from sheet metal without any extremities to be connected, if desired, without departing from the spirit of my invention. If so made, it will be obvious that there would be no protruding point P to take into and necessarily mar the lower side of the whiffletree. The sides of the oval are bent upward between its ends, and each side is provided at about its center with an eye I, as seen.

The letter A designates the arm of my improved hook. This is also preferably made from a single piece of wire of substantially triangular configuration, the base extending across the center of the oval and through the two eyes I, between which it is deflected to the rear or inwardly along the whiffletree in a cam, as at C, and just outside the eyes this wire bends sharply outward into two converging members extending along above the whiffletree and turned down at their outer ends. In Fig. 1 I have shown these downturned ends as making a metallic foot adapted to rest upon a small piece of felt, leather, or other material L, secured upon the whiffletree in proper position to receive the pressure of the foot and prevent the scratching of the paint; but in Fig. 2 I have shown a small foot F', as of leather, rubber, or other proper material, which might be attached to and carried by the downturned ends of the wire, so that the provision of the cushion on the whiffletree would not be necessary.

With the above construction of parts and their assembly as seen in Fig. 2 my improved device is attached to any whiffletree by simply depressing the ends of the oval until they can be passed under the whiffletree, while the cross-bar and cam of the arm at the center of the oval passes over such whiffletree, thus causing the spring action of the oval to be exerted to draw said cam downward on the wood of the tree. This naturally raises the inner or cam end of the arm A, and hence forces its outer end downward, and the result is that the foot F' is caused to rest upon the reduced outer end of the whiffletree, as shown. Obviously the trace is fastened in place by first raising the foot slightly, then passing the cockeye over the point of the

tree, and then releasing the foot, which is forced and held down upon the whiffletree at a point just outside the trace, as illustrated.

It will be obvious that the ends of the oval 5 could be sprung farther down, if necessary, in order to apply the device to a whiffletree of larger size; also, that by depressing such ends the entire device could be adjusted longitudinally of the whiffletree and set where desired, and it will be clear that in so setting it the point P, if used, will be forced upward into the lower side of the tree, but if not used the spring action of the oval (which the coiled eyes I I assist rather than otherwise) will be sufficient to hold the device in position under all ordinary circumstances.

Instead of the eye F and point P, I might employ a staple, as seen at p in dotted lines, taking over the inner end of the oval and 20 passing into the tree. The outer end of the oval may be used to hold the cockeye in position from an inward movement, while the foot prevents its outward movement. A tube 25 of leather or other soft material can be used on the cam, as seen at C, or a sheet may be applied to the tree, as at L, to prevent scratching. The arm A may be thrown clear back in the act of applying the cockeye or removing it, and other details may be elaborated at 30 pleasure. This device also prevents the rattling of parts, as will be clear.

I do not limit myself to the precise shapes, materials, proportions, or finished parts, as considerable change can be made without departing from the spirit of my invention. As 35 above stated, the flat eye F and point P could be omitted entirely, if desired, and for the soft foot F' at the outer end of the arm a metallic foot could be used, with or without 40 the cushion L on the tree, according to the finish of the latter.

What is claimed as new is—

1. In a whiffletree-hook, the combination 45 with an oval loop of wire whose ends stand beneath the whiffletree and whose center is raised, one extremity of the wire having a flat eye at one end of the oval and the other extremity being bent upward and passing through such eye; of a hook-shaped arm piv- 50 oted to the raised center of the oval, and

means for normally depressing its outer end or foot into contact with the whiffletree, as set forth.

2. In a whiffletree-hook, the combination 55 with an oval loop of spring material whose ends stand beneath the whiffletree and whose center is raised; of an arm of wire passing under the center of said loop and across the whiffletree and there having an inwardly-projecting cam, and a downturned foot at the 60 outer end of the arm, as set forth.

3. In a whiffletree-hook, the combination 65 with an oval loop of spring material whose ends stand beneath the whiffletree and whose center is raised and has eyes at opposite sides 70 of said tree; of an arm of wire passing through said eyes and across the whiffletree and there bent to the rear to form a cam, the wire outside the eyes extending outward along the 75 whiffletree and converging, and the ends of the wire being turned downward into a foot, as set forth.

4. In a whiffletree-hook, the combination 80 with a loop removably and adjustably mounted on the tree with eyes at the sides thereof, said loop exerting a spring action to depress its eyes; of a substantially triangular arm of wire whose base passes through said eyes and is bent inward on the whiffletree between them to form a cam, and whose sides converge 85 beyond said eyes and are bent downward at their outer ends into a foot, and means for preventing the abrasion of the whiffletree by such foot, as set forth.

5. In a whiffletree-hook, the combination 85 with a spring-support; of a hook-shaped arm mounted therein with its body standing along above the whiffletree and its outer downwardly-bent end normally depressed by the action of the spring, a foot carried by such 90 outer end, and a soft cushion secured upon the tree beneath the foot, as and for the purpose set forth.

In testimony whereof I have hereunto subscribed my signature on this the 17th day of 95 May, A. D. 1897.

ADDISON D. LODGE.
